UNDERWATER LIGHT

Allan Thomas Beer, Redwood City, Calif., assignor to Darrell-Allan Corporation, Belmont, Calif.

Filed Jan. 17, 1972, Ser. No. 218,653

Term of patent 14 years

Int. Cl. D26—02

U.S. Cl. D48—24 R

FIG. 1 is a perspective view of an underwater light showing my new design;

FIG. 2 is a top plan view thereof;

FIG. 3 is a side elevational view thereof, the opposite side being substantially identical except for the omission of the switch;

FIG. 4 is a rear elevational view thereof; and

FIG. 5 is a front elevational view thereof.

I claim:

The ornamental design for an underwater light, substantially as shown and described.
